UNITED STATES PATENT OFFICE.

FREDERICK D. TAYLOR, OF HARTFORD, CONNECTICUT, ASSIGNOR TO THE HARTFORD FRUIT JAR COMPANY, OF SAME PLACE.

BOTTLE-STOPPER.

SPECIFICATION forming part of Letters Patent No. 337,458, dated March 9, 1886.

Application filed December 31, 1885. Serial No. 187,219. (No model.)

To all whom it may concern:

Be it known that I, FREDERICK D. TAYLOR, of Hartford, in the county of Hartford and State of Connecticut, have invented certain new and useful Improvements in Bottle and Jar Stoppers, of which the following is a full, clear, and exact description, whereby any one skilled in the art can make and use the same.

My improvement relates to the class of stoppers that are attached more or less permanently to the bottle, and are adapted to be swung into position so as to close the bottle, or temporarily to one side to open the bottle.

The object of my improvement is to provide a cheap, simple, and effective device that shall be particularly adapted for use on bottles or cans intended to contain milk, although its use is not limited by the particular character of the contents of the jar or bottle.

My improvement consists of a swinging bail with its pivots held in sockets in or on diametrically-opposite sides of the bottle-neck, with a bowed portion adapted to swing directly over the mouth of the bottle and supporting a screw hinged thereto by an opening through its head or stem, and a stopper having a central threaded socket that enables it to be fitted upon the threaded shank of the screw, and in details of the construction and combination of the several parts, as more particularly hereinafter described, and pointed out in the claims.

Referring to the drawings, Figure 1 is a front view of the upper part of a bottle fitted with my improved device, and shown with the stopple in position, sealing the bottle. Fig. 2 is a side view of the same, showing the stopper lifted to open or unseal the bottle, and showing in dotted outline the position of the stopper when swung aside to give access to the mouth of the bottle. Fig. 3 is a detail view of the several parts or elements making up the stopper, the wire frame or bail and the screw being shown in elevation and the stopper in central section. Fig. 4 is a view in central section of an alternate form of stopple.

In the accompanying drawings, the letter *a* denotes a bottle or jar, of any desirable material—as glass—and having on diametrically opposite sides of the neck the pivot-sockets *b*, that are preferably formed in the substance of

the bottle in the process of molding it. The particular form of the socket or the means by which it is held at a fixed distance from the mouth of the bottle are not material to my improvement. 55

The bail *c* is made, preferably, of wire, with pivots *c'*, formed by bending the ends inward, and the side parts of the bail of a length to allow the bow *c²* to swing clear of the mouth of the bottle to which it is attached a sufficient distance to allow room for the stopper *d* between them. This bail is preferably formed with a re-entrant bend, *c³*, in the bow, and it supports a screw, *e*, that is hinged to it. The object of the bend *c³* is to retain the screw *e* in the central part of the bow to get an additional spring effect, that relieves the upward pull on the pivots when the bottle is closed, and it also forms two convenient loops, that 70 serve as means for holding and carrying the bottle on the fingers of the hand.

The screw *e* is made of any convenient and desirable material—as iron—with a wide thread of a sharp pitch, and the upper end of the stem has a hole, *e'*, through which the bail is passed to hinge it thereto, so as to allow the screw to swing upon it, but not to rotate axially of the screw. 75

The stopper *d* is made, preferably, of wood, 80 although the particular liquid that the bottle is intended to hold will in some degree govern the choice of material; but wood or a like substance that will not deleteriously affect the contents of the bottle may be used, the screw-socket *d'* being formed in the center of the stopper or plug and threaded to fit the thread of the screw. 85

On its under side the stopper may be hollowed out, with a rim or flange, *d²*, that fits 90 outside of the rim *a'* on the mouth of the bottle, as shown in Fig. 2; or it may be of a form adapted to fit within this rim.

A packing washer or disk of elastic material—as paper or rubber—may be used beneath 95 the stopper to make an air-tight or securely-sealed joint.

The bail *c*, if of wire, is bent to shape, Fig. 3, by simple tools and cheap labor.

The screw *e* may be cast to final shape of 100 iron, then cleaned and tinned, and the plug may be turned to shape in a wood-working

machine that produces great numbers in a short time.

These several parts are assembled by thrusting the bail through the pivot-hole in the screw and then bending the bail to shape. 5 The stopper is screwed upon the screw and the pivots of the bail sprung into the sockets on the bottle.

By turning the stopper it may be closed 10 upon the bottle-mouth or lifted from it.

The above-described methods of making the several parts are not essential so long as the parts are capable when combined and attached to a bottle of effecting the purpose desired and outlined in a manner and by means 15 of the same in kind and effect.

I claim as my improvement—

1. In combination with a bottle bearing lateral bail-sockets, a swinging bail with pivot-20 supports, and a bow supporting a screw hinged

thereto, and a stopper or plug attached to the screw by a threaded central socket, the side parts of the bail being of a sufficient length to suspend the stopper between the bow and the bottle-mouth, all substantially as described. 25

2. In a bottle-stopper fastening, in combination, a bail, c , with pivots c' , and bow c^2 with re-entrant bend c^3 , a screw, e , hinged to the bow, and the stopper d , borne on the screw, all substantially as described. 30

3. In combination with a bottle, a bail pivoted thereto and adapted to swing across the mouth of the bottle, and a rotary stopper or plug suspended from the bow of the bail by a screw held against axial rotation, all substantially as described. 35

FREDERICK D. TAYLOR.
